UNITED STATES PATENT OFFICE.

CLAUS O. BRANDELL, OF CHICAGO, ILLINOIS.

MACHINE FOR MAKING CONCRETE BLOCKS.

No. 852,764.

Specification of Letters Patent.

Patented May 7, 1907.

Application filed October 4, 1906. Serial No. 337,419.

To all whom it may concern:

Be it known that I, CLAUS O. BRANDELL, a citizen of the United States, residing at Chicago, in the county of Cook and State of Illinois, have invented certain new and useful Improvements in Machines for Making Concrete Blocks, of which the following is a specification.

My present invention relates to improvements in a machine to be used for manufacturing blocks from plastic or cementitious material to be employed for building or structural purposes, and it consists in certain peculiarities of the construction, novel arrangement, and operation of the various parts thereof, as will be hereinafter more fully set forth and specifically claimed.

While the invention is more especially intended to be used for manufacturing concrete blocks having apertures or air spaces therein, yet it is applicable for use in making brick, terra-cotta blocks, and the like, of similar form, and it has for its principal object to afford a machine of the above-named character by means of which blocks of the desired formation and size may be quickly molded or formed thereby, and which machine shall be simple and inexpensive in construction, strong, durable and effective in operation.

In order to enable others skilled in the art to which my invention pertains, to make and use the same, I will now proceed to describe it, referring to the accompanying drawings, in which—

Figure 1 is a view in side elevation of a machine embodying my invention, showing by continuous lines the cores or plungers withdrawn from the mold-box, and illustrating them by dotted lines inserted into the mold-box. Fig. 2 is a cross-sectional view of one of the hinged doors of the mold-box. Fig. 3 is a plan view of the machine, showing the plungers or cores withdrawn from the mold-box, and illustrating the operating lever used for projecting and withdrawing the cores in place. Fig. 4 is a detached face view of a bracket which supports the outer ends of the cores or plungers. Fig. 5 is a detail view of one of the arms used for automatically closing the doors of the mold-box when the latter is being turned to its normal position. Fig. 6 is a plan view of the bed or horizontal portion of the supporting frame, showing a part of the base of the mold-box mounted thereon. Fig. 7 is a detached plan view of a clip or bar used for securing the core supporting bracket

on its track or guide rods. Fig. 8 is a side view thereof. Fig. 9 is a cross-sectional view of the bed of the supporting frame taken on line 9, 9 of Fig. 6 looking in the direction indicated by the arrows. Fig. 10 is a plan view of a bar or clip used for supporting the rails or guide rods on which the core carrying bracket travels. Fig. 11 is a side view thereof. Fig. 12 is a central vertical sectional view taken longitudinally through the supporting frame, but transversely through the mold-box, showing the bed of the supporting frame shortened for the convenience of illustration. Fig. 13 is a view partly in section and partly in elevation taken on line 13, 13 of Fig. 6 looking in the direction indicated by the arrows, but showing the mold-box and plungers or cores in position on the supporting frame. Fig. 14 is a sectional view of a portion of the rear wall of the mold-box and a part of the bed of the supporting frame, showing the manner of connecting said parts together. Fig. 15 is a central vertical sectional view taken longitudinally through a portion of the supporting frame and transversely through the mold-box, showing the latter by continuous lines in the position it will assume when the molded block is to be removed therefrom, and by vertical and horizontal dotted lines in its normal position. Fig. 16 is a plan view of a portion of the supporting frame and the mold-box, showing the position the parts will occupy when the block is to be removed;—and—Fig. 17 is a fragmental perspective view of the base frame of the mold-box.

Like numerals of reference, refer to corresponding parts throughout the different views of the drawings.

The bed or horizontal portion of the supporting frame is designated by the reference numeral 20, and consists of an elongated rectangular part having a central opening 21 for the passage and operation of certain parts of the machine, and is provided on each of its sides at one of its ends, which I will term the forward or front end, with lateral and horizontal extensions 22, which are supported by side pieces 23, each of which has a front 24 and rear leg 25, provided with feet 26 to rest on the ground or floor. The legs 24 and 25 of each of the end pieces 23 are connected together and braced by means of a bar or portion 27, which extends longitudinally with the supporting frame, and said pieces 23 are connected together transversely of the supporting frame and braced at their

front portions by means of a yoke or part 28, which is secured at its upper portion by means of bolts 29 passing through the down-turned portion of the front transverse part of 5 the bed 20 of the supporting frame, the sides and ends of which bed are angular in cross-section, as shown in the drawings. The upper portion of each of the pieces 23 is also secured by means of bolts 30 to the down-turned and longitudinally extending portions of the extensions 22, which are also made angular in cross-section. Projecting forwardly and horizontally from each of the extensions 22 is an arm 31, each of which is 10 provided on its inner surface near its front portion with spaced apart lugs 32 to receive therebetween the shanks of brackets 33, which are used to support the front plate of the mold-box with the mold block thereon 15 20 when the said box is tilted to the position shown by continuous lines in Fig. 15, for the purpose of removing the block. The shanks of the brackets 33 are provided with slots 34 for the reception of bolts 35, which pass 25 through suitable openings in the front portions of the arms 31, thus adjustably securing the brackets 33 in position on said arms, each of which is provided on its upper surface at its inner end with an apertured lug 36, to 30 which are secured by means of pivots 37 extensions or lugs 38 located on the front portion of the base frame 39 of the mold-box, which frame is preferably made of material angular in cross-section, as shown, and has at 35 the front portion of each of its ends a laterally and horizontally projecting apertured extension 40, each of which has an upward projection 41, the inner surface of which is inclined, as will be clearly understood by reference to Fig. 17 of the drawings. The base 40 frame 39 also has at the rear portion of each of its ends a laterally and horizontally extending apertured projection 42, between which projections and the extensions 40 at 45 each end of the frame 39 is extended the lower portion of one of the doors 43 used for closing the sides of the mold-box, which lower portions of said doors are pivotally secured to the projections 42 and extension 40 50 by means of pintles passing through the openings therein.

As is clearly shown in Figs. 1 and 17 of the drawings, the extensions 38 and beveled projections 41 on the base frame 39 of the mold-box extend upwardly some distance above the upper surface of the rails of said frame, and that the lower portion of the doors 43 will project downwardly between the extensions 40 and lugs 42, the side edges of said doors being recessed for this purpose and so that the projections 41 will rest against the outer surface of the doors 43, thus restricting their outward movement. Located on the upper surface of the frame 39 and secured thereto by means of a screw bolt 44, which

passes through the rear portion of the frame 39 at about its middle, is the base plate 45 of the mold-box, which has a flat upper surface, but has its edges downturned, and coincides transversely in size with the said base frame, 70 so that its front edge will rest against the upwardly extending portions of the lugs 38 and its rear edge against the front surface of the rear plate of the mold-box, when the base frame thereof is in its normal position. 75

As shown in Figs. 1, 3, 6, 14 and 16 of the drawings, each of the lateral extensions 22 of the bed 20 of the supporting frame is provided with a rearward projection 46 located at some distance from the sides of the bed 20, 80 so as to provide spaces for the reception of the lower portion of the rear plate 47 of the mold-box, which is secured in an upright position by means of bolts 48, which pass through the lower part of said plate and the 85 rear transverse portion of the extensions 22 of the bed of the supporting frame. This rear plate is provided with a number of openings 49, usually two, substantially rectangular in shape, for the reception and operation 90 of the core plungers. Adjustably secured to the rear surface of the plate 47 at the upper portion of each of its ends, by means of screw bolts 50 taking therein, are cam-arms 51, which extend laterally, then downwardly 95 and then forwardly from the ends of the rear plate 47 and near the side doors 43 of the mold-box, which are for the purpose of engaging cams 52, one of which is diagonally located on the outer surface of each of the side doors 43, so that said doors will be firmly held in their vertical or normal positions. As shown, each of the doors 43 is provided on its outer upper portion with a laterally projecting handle 53 used for manipulating them, 100 and is also preferably inwardly and transversely bellied as at 54 to create a depression in the ends of the block, but said bellied portions of the doors may, if desired, be omitted. Each of the doors 43 is provided with a chamfer 55 at its edge adjacent to the rear plate 47 of the mold-box to receive the ends of said plate when the doors are in their normal positions, as shown in Fig. 3, and each of said doors is provided near its front edge, when in 105 said position, with a vertical groove 56, to receive the ends of the pallet 57 or front plate of the mold-box. This pallet or front plate is provided with one or more openings 58 to register with the openings 49 in the rear plate 110 47, and are for the reception and operation 115 of the cores or plungers.

Horizontally located in parallelism with one another below the bed 20 of the supporting frame, and extending longitudinally 115 therewith, are two guide rails or rods 59, the front ends of which are supported on the front transverse portion of the bed 20 by means of a clip or bar 60, which has near each of its ends recesses 61 to receive said rods or 120

rails, and which is fastened to the said portion of the bed by means of bolts 62, and the rear ends of said rods are similarly connected to the rear transverse portion of the bed, as 5 is clearly shown in Fig. 12 of the drawings. Movably mounted on the rails 59 is the core carrying bracket or carrier 63, which consists of a vertical plate 64 having at its lower portion a horizontally and forwardly extended 10 portion 65, to which are transversely bolted at suitable distances apart a number of bars or clips 66, which are preferably made of channel iron, as shown in Figs. 7, 8 and 12, and have at each of their ends recesses 67 to 15 receive the rods or rails 59 on which the carrier or bracket 63 travels.

As shown in Fig. 4, the bracket 63 is provided with horizontal slots 68 in its lower portion to receive the sides of the bed of the 20 supporting frame, so that the upper portion or plate 64 of the carrier 63 will extend above the bed, yet will be permitted to travel freely back and forth thereon. The plate 64 of the carrier or bracket 63 is formed with a number 25 of slots 69, through which are passed bolts 70, which also pass through a downward extension 71 on the rear end of each of the cores 72, which are of a size and shape to fit and correspond with the openings 49 and 58 30 in the rear and front plates, respectively, of the mold-box. These cores are preferably slightly tapered toward their front ends to permit of their easy withdrawal from the mold-box when it is filled, and are adjust- 35 ably secured on the carrier or bracket 63 by means of the bolts 70, which, as before stated, pass through the slots 69 in the plate of the carrier, which plate is provided on its rear surface with a horizontal extension 73, 40 which has an elongated opening 74 at about its middle, for the reception and operation of the operating lever 75, which is fulcrumed at its lower end to one of the supporting legs 25 and extends diagonally therefrom up through 45 the opening 21 in the bed of the supporting frame and through the opening 74 in the extension 73 of the carrier or bracket, as is clearly shown in Figs. 1 and 3 of the drawings.

While I have shown the carrier or bracket 50 63 provided with two cores or plunges 72, yet I do not desire to be limited to said number of cores, as I may employ one or more without departing from the spirit of the invention.

The operation of the machine is as follows:— 55 When it is desired to mold a block, the side doors 43 and pallet or front plate 57 are placed in the positions shown in Figs. 1 and 3 of the drawings, in which positions they will be firmly held in place by means of the arms 60 51, which engage the cams 52 on the side doors, and also by means of the upwardly extending parts of the lugs or extensions 38, which portions will engage the lower part of the pallet. The cores are then retracted to 65 the position shown in said figures, when a

sufficient quantity of concrete, cement, or other suitable material to give a suitable facing or finish, is placed in the box so as to fill it up to, or a little above the lower edges of the openings 49 and 58 in the rear and front 70 plates thereof, which said material may be tamped, after which the cores are projected by moving the lever 75 forwardly to the position shown by dotted lines in Fig. 1, when the box may be filled with suitable material 75 around the cores and tamped, the cores 72 may be withdrawn by turning the lever 75 to the position shown by continuous lines in Fig. 1 of the drawings. To remove the block, the mold-box is turned from the position shown by the vertical and horizontal dotted lines in Fig. 15 to that shown by continuous lines in said figure, when the pallet or front plate 57 will rest on the upper edges of the brackets 33, which are adjustable, as 80 before stated. When the mold-box is in the position shown by continuous lines in Fig. 15, it is apparent that the side doors 43 may be turned outwardly to about the position shown in Fig. 16. To again prepare the 85 mold-box for the reception of the material to make another block, the base frame 39, bottom 45, and side doors 43 are turned back so as to assume the positions shown by vertical and horizontal dotted lines in Fig. 15, in 90 which operation the cam-arms 51 will strike against the cams 52, and thus hold the doors 43 against outward lateral movement, and it will be understood that the chamfers 55 will engage the ends of the rear plate 47 of the 95 box. When the parts are thus located, the pallet 57 on which the molded block rests may be removed and deposited at a suitable point, when another pallet or front plate 57 may be inserted into the grooves 56 of the 100 doors until it rests on the bottom 45, when the filling of the box may be proceeded with and the above-named operation repeated. To prevent the mold-box from falling too far 105 so as to injure parts of the machine after the moldied block and pallet 57 have been removed from the brackets 33, the lower portions of the lugs or extensions, which are slightly curved as shown in Figs. 12, 15 and 110 17, will strike against the front transverse portion of the bed of the supporting frame, thus causing the parts of the box to assume the positions shown by inclined dotted lines in Fig. 15, and thereby preventing any further downward movement. When the box 115 is turned to the last named position, after the moldied block and pallet have been removed, it is apparent that by unscrewing the bolt 44, the base-plate 45 may be removed from the base-frame 39, and another one substituted 120 therefor, or the box may be readily cleaned of any material that may adhere thereto. By providing the base-frame 39 with the inclined or beveled projections 41 at its ends, and by employing the cams 52, the lower ends 125 130

of which are beveled, as shown, on the doors 43, it is obvious that said doors will be held at such angles with respect to the frame 39 and arms 51, that said arms will strike the 5 beveled ends of the cams 52, in the operation of returning the base-frame to its initial position, and will thus automatically cause the doors to assume their normal positions and be securely held in place.

10 It will be obvious from the above description that the apparatus is susceptible of considerable modification without material departure from the principles and spirit of the invention, and for this reason I do not desire 15 to be understood as limiting myself to the precise form and arrangement of the several parts herein set forth in carrying out my invention in practice.

Having thus fully described my invention, 20 what I claim as new and desire to secure by Letters-Patent, is—

1. In a machine for making concrete blocks and the like, the combination with a supporting-frame, of a detachable mold-box 25 mounted thereon and a part of the same pivotally connected thereto at its front portion, said box consisting of a fixed and upright apertured rear plate, a removable pallet, a base-frame provided with a bottom for said 30 box, and a door hinged near one of its edges to each end of the base-frame, and means on the said frame to hold the doors in angular relation thereto in the operation of removing the block.

35 2. In a machine for making concrete blocks and the like, the combination with a supporting-frame, of a detachable mold-box mounted thereon and a part of the same pivotally connected thereto at its front portion, 40 said box consisting of a fixed and upright apertured rear plate, a removable pallet, a base-frame provided with a bottom for said box, and a door hinged near one of its edges to each end of the base-frame, means on the 45 said frame to hold the doors in angular relation thereto in the operation of removing the block, a core movable horizontally on the frame and adapted to fit in the aperture of said rear plate, and means to move the core 50 back and forth.

55 3. In a machine for making concrete blocks and the like, the combination with a supporting-frame, of a detachable mold-box mounted thereon and consisting of an upright fixed rear plate having an opening therein for a core, a base-frame provided with a bottom for the box and pivotally connected at its front portion to the supporting-frame, a door pivotally connected near one of its 60 edges to each end of said base-frame, and a pallet removably located between said doors at their front portions, a projection at each end of the base-frame to restrict the movement of said doors, a core movable horizontally on the frame and adapted to fit in the 65

opening of the rear plate, means to move the core back and forth, and brackets on the frame in front of the mold-box to support it in its tilted position.

4. A mold-box consisting of a fixed and 70 upright apertured rear plate, a removable pallet or front plate, a base-frame provided with a bottom for said box, and a door hinged near one of its edges to each end of the base-frame, means at each end of the 75 base-frame to restrict the movement of said doors, and means at each end of the rear plate and on each of the doors to co-act so as to automatically close the doors when the base-frame is returned to its initial position. 80

5. In a machine for making concrete blocks and the like, the combination with a supporting-frame, of a detachable mold-box mounted thereon and a part of the same pivotally connected thereto at its front portion, 85 said box consisting of a fixed and upright apertured rear plate, a removable pallet or front plate, a base-frame provided with a bottom for said box, and a door hinged near one of its edges to each end of the base-frame, a cam-arm located on each end of the rear plate, a cam-block located on the outer surface of each of said doors to co-act with the said cam-arms so as to automatically close the doors when the base-frame is re-turned to its initial position. 95

6. In a machine for making concrete blocks and the like, the combination with a supporting-frame, of a detachable mold-box mounted thereon and a part of the same pivotally connected thereto at its front portion, 100 said box consisting of a fixed and upright apertured rear plate, a removable pallet or front plate, a base-frame provided with a bottom for said box, and a door hinged near 105 one of its edges to each end of the base-frame, a cam-arm located on each end of the rear plate, a cam-block located on the outer surface of each of said doors to co-act with the said cam-arms so as to automatically close the 110 doors when the base-frame is returned to its initial position, a carrier or bracket movable horizontally on the supporting-frame and having a transversely elongated opening in its rear portion, a core mounted on said carrier and adapted to fit in the aperture of said 115 rear plate, and a lever fulcrumed on the supporting-frame and extended through the transverse opening in the carrier for the core. 120

7. In a machine for making concrete blocks and the like, the combination with a supporting frame, of a detachable mold-box mounted thereon and consisting of an upright fixed rear plate having an opening 125 therein for a core, forwardly extending cam-arms secured on said plate at each of its ends, a base-frame provided with a bottom for the box and pivotally connected at its front portion to the supporting frame, a door pivot- 130

ally connected near one of its edges to each end of said base-frame, a cam-block located on the outer surface of each of said doors to engage the cam-arms on the said rear plate, and a pallet or front plate removably located between said doors at their front portions, a carrier movable horizontally on the supporting frame, a core mounted on said carrier and adapted to fit in said opening of

the rear plate, a lever fulcrumed to the supporting frame and in engagement with the carrier, and means on the front portion of the supporting frame to support the mold-box in its tilted position. 10
